Primary Examiner—Robert M. Spear

(74) Attorney, Agent, or Firm—Wallenstein & Wagner, Ltd.

(57) CLAIM

I claim the ornamental design for a sign post, as shown and described.

DESCRIPTION

FIG. 1 is a perspective view of a sign post, incorporating the new design;

FIG. 2 is a front elevation view of the sign post of FIG. 1; FIG. 3 is a side elevation view of the sign post of FIG. 1; and,
